SCREENING APPARATUS

Thomas Sandy, Goderich, Ontario, Canada

Application January 21, 1933, Serial No. 652,792
In Canada August 18, 1932

4 Claims. (Cl. 209—284)

This invention relates to screening apparatus, more particularly a combination apparatus which has associated therewith means for continuously screening and crushing or grinding materials to a predetermined grade or fineness, and although the invention may be applied to various uses, it will in the present instance be referred to rock crushing and screening to which it has already been successfully adapted.

- 10 Primarily, in unit form, the present invention continuously screens, elevates, crushes and rescreens materials. The screen in this particular case performs several functions, the principle of which is the continuous elevating and screening properties, it is therefore one of the objects of the invention to provide a screening apparatus of this character which embodies means for continuously screening, elevating, crushing and rescreening materials in a machine of unit form.
- 15 Another object of the invention is to provide a device of this character which, when in operation, conducts unscreened materials from one side of the screen to the elevating means.

20 A further object of the invention is to provide a device of this character composed of few parts and efficient in operation and which may readily be transported from place to place and set in operation.

25 A still further object of the invention is to embody in the apparatus a common collector for the screened materials from which they are conducted to a common delivery by the operation of the rotating screen.

30 Yet another object of the invention is to provide a unitary device of compact form which may be mounted on a motor vehicle and driven from the source of power required for operating the motor vehicle.

35 With the foregoing and other objects which will become apparent as the description proceeds, the invention consists of the novel combination and arrangement of parts hereinafter described in detail and illustrated in the accompanying drawing in which:

40 Figure 1 is a front elevation of my improved screening apparatus as a whole.

Figure 2 is an end view of Figure 1.

45 Figure 3 is an enlarged sectional detail showing one of the carrier buckets and its mounting and

50 Figure 4 illustrates in fragmentary detail a positive drive means for the screen.

55 Referring now to the details of structure and arrangement of the screening apparatus wherein like letters and numerals of reference indicate

corresponding parts in the different views, the letter A designates the apparatus as a whole and in the main includes a rotatable screen B and a crusher C.

The crusher may be of any well known and practical type and includes a hopper 10 and a housing 11, mounted within the housing are the usual crushing elements. The crusher C as a whole may conveniently be mounted on the chassis of a motor vehicle which I have indicated 10 by the dotted lines 12 or, if transportation means is unnecessary the apparatus may be mounted upon a suitable stationary platform or stand.

Coming now to one of the essential features of the invention, this comprises a rotatable screen 15 B which includes screen 14 which may be of the wire mesh or perforated metallic type and provided with side walls 15. The screen is preferably of annular formation and is mounted, as particularly indicated in Figure 1, so as to encircle the crusher member C.

While in practice the crusher might be mounted at one side of the screen, experiment has shown that most satisfactory and efficient results have been obtained by mounting it within 25 the screen.

The support means for the screen comprises pairs of grooved or fluted roller members 16 and 17 mounted on shafts 18 and 19 and provided with bearings 20 and 21. The rollers 16 and 17 support and rotate the screen member and may in turn be supported in any practical manner such as for example, brace members 22 and 23 which I have indicated by dotted lines as connecting the bearing members with the crusher 30 housing.

35 For practical purposes the roller members are preferably mounted on annular tracks 24 and 25 which may be of the T, angle or channel type 40 and are positioned at the edge of the screen so as not to interfere with the screening properties thereof. Drive means for rotating the screen may be of the friction or gear type. The friction type is shown in Figure 1 while an alternative in the form of a positive type is shown in Figure 4.

45 Power means for operating the screen may be taken from the power means for operating the crusher or, when the apparatus is mounted on a 50 motor vehicle, energy may be taken from that source and employed to drive the necessary operative parts. Such power means would preferably take positive form for example, a drive chain which in so far as the screen drive is con- 55

cerned, would be connected to the gear 26 mounted on the shaft 18.

A further essential feature of the invention is the means for conducting uncrushed or partly crushed rock or other material from the base of the screen to the crusher. This means comprises a series of carrier buckets of the dump type 27, 28 and 29 pivotally mounted as indicated at 30 on support members 31. These buckets, it will be observed by reference to Figure 2, are preferably mounted to one side of the screen and while in this relative position efficiently perform their function, they do not interfere with the screening operation.

15 Normally when a bucket is empty it will, in accordance with its position, move into engagement with the screen by gravity, such relative position being shown by the buckets 27 and 28. Then, as the buckets move upwardly with the 20 rotation of the screen, they are prevented from responding to gravitational movement by an arcuate guide member 32. Immediately however, the bucket passes the extremity of the guide, the 25 pivotal mounting and force of gravity will cause the bucket to dump the contents thereof into the hopper 10, thus the buckets continuously fill with larger sized rock or materials which are 30 conveyed or carried upwardly and automatically dump such contents into the hopper for crushing or re-crushing, the screening meantime is continuously in operation.

The material carrying buckets 27, 28 and 29 hereinbefore referred to have been mentioned as 35 gravitationally operable buckets however it will be clearly understood that buckets of the mechanical or positive dump type may be substituted for such type or arrangement without departing from the spirit of the invention.

In addition to the means for carrying the 40 materials from the base of the screen to the crusher member, I provide means for causing unscreened materials to so move that during the rotation of the screen they are carried from one side of the screen to the other in such a manner that the dump bucket is automatically filled by the 45 rotation of the screen. This automatic bucket filling means comprises angularly disposed plate or bar members 27a mounted on the inner face of the screen and preferably positioned adjacent the open or filling end of the respective buckets. 50 With this particular arrangement it will be observed that as the screen rotates the angularly disposed members 27a will be engaged by the unscreened rocks or like materials within the 55 screen and thus readily conducted toward and into the bucket members.

Positioned at the base of the screen and situated therebeneath is an arcuate trough 33. This trough is adapted to receive the materials which 60 have been screened during the rotative movement of screen B.

Cooperating with the trough member are a 65 series of vanes or blade members 34 which are mounted around the periphery of the screen and preferably of substantially scoop shape. It will be readily observed by reference to the drawing that as the screen is rotated the blade members 34 travelling through the trough 33 will carry the screened materials therefrom and such materials may then be dumped upon an endless v belt or the like 35 when it is elevated for wagon loading or otherwise removed.

The conduction of uncrushed rock or other 75 materials to the screen in the first instance may take any practical form and I have indicated in

Figure 2 a conveyor belt 36 through which medium the uncrushed materials are carried to the screen from a source of supply.

In operation, the crusher is set in motion and the screen in rotative movement. Uncrushed rock, gravel or the like is then fed to the interior base of the screen. As the screen rotates the finer materials will be automatically screened, the larger and heavier materials not passing through the screen are carried over to one side 10 and picked up by the buckets 27, 28 and 29 and carried upwardly to be automatically dumped in the crusher hopper. The crusher being in continuous operation crushes and discharges the 15 crushed materials directly to the base of the screen where it is further screened, thus there is a continuous screening, elevating, crushing and re-screening operation. As the operation continues the blade members 34 mounted on the periphery of the screen, carry the screened material 20 from the trough 33 to a suitable conveyance which may take the form of an endless belt, bucket conveyor or the like from whence it is carried to a loading wagon, storage chute or common 25 dump.

From the foregoing it will be observed that I have devised a simple, practical and novel means for continuously elevating materials by a screening member for crushing purposes and at the same time continuously screen the materials and 30 while an embodiment of this device is herein disclosed changes could be made in its practical design and many apparently widely different embodiments of the invention constructed without departing from the spirit or scope thereof. It 35 is intended therefore, that all matter contained herein shall be interpreted as illustrative rather than in a limitative sense.

What I claim as my invention is:

1. Screening apparatus for continuously screening and crushing materials comprising a rotatably mounted screen, a crushing device cooperatively associated with the screen, a series of carrier buckets pivotally supported within the screen, guide means for retaining the carrier buckets and regulating the dumping movement thereof and trough means for collecting the screened materials.

2. Screening apparatus of character described for continuously screening and crushing materials comprising a rotatably mounted screen, a crushing device located within the screen and provided with a hopper, a series of carrier buckets associated with the screen extending to a point less than the width of the screen and in 55 radial alignment with the crusher hopper, guide means for regulating the upward movement of the carrier buckets, trough means for collecting the screened materials, a plurality of blade members associated with the periphery of the screen for discharging screened materials from the trough and means for rotatably supporting the screen.

3. In screening apparatus of the character described for continuously screening and crushing materials, a rotatable screen, a crushing device mounted for operation within the screen, means carried by the screen for conducting materials to and automatically dumping them into the crusher device, support means for rotatably supporting the screen and means for automatically guiding unscreened materials to the means for conducting materials to the crusher device.

4. Screening apparatus of the character described for continuously screening and crushing 75

materials comprising a rotatably mounted screen and a receiver for oversize materials, a series of pivotally mounted bucket members carried by the screen and adapted to conduct materials to the said receiver, guide means for regulating the dumping movement of filled carrier buckets, trough means for collecting the screened materials and means for discharging the screened materials from the trough.

THOMAS SANDY.
